UNITED STATES PATENT OFFICE.

WILLIAM H. GILLEN, OF MILWAUKEE, WISCONSIN.

WATER BARRIER.

Application filed September 11, 1925. Serial No. 55,779.

This invention relates to improvements in water barriers, and more particularly to revetments and breakwaters.

It is one of the objects of the present invention to provide a revetment or the like of sectional construction.

A further object of the invention is to provide a revetment or the like formed of reinforced concrete piles arranged to be jetted into place.

A further object of the invention is to provide a revetment or the like having precast stiffening members arranged to be locked in position.

15 A further object of the invention is to provide a revetment or the like in which certain portions are precast, while other portions are cast in position during the process of construction.

20 A further object of the invention is to provide a revetment or the like effectively braced and strengthened to withstand weather and waves.

A further object of the invention is to 25 provide a revetment or breakwater of very simple construction, strong and durable, easy to erect, and well adapted for the purposes described.

With the above and other objects in view, 30 the invention consists of the improved revetment or the like, and its parts and combinations as set forth in the claims, and all equivalents thereof.

In the accompanying drawing in which 35 the same reference characters indicate the same parts in all of the views:

Fig. 1 is a perspective view of a reinforced concrete sheet pile as used in the construction of revetments and breakwaters in accordance with the invention;

Fig. 2 is a perspective view of a revetment;

Fig. 3 is a cross sectional view thereof showing a slightly modified form of rail and wale construction;

Fig. 4 is a plan view thereof;

Fig. 5 is an enlarged detail view showing the means for locking the stiffening members or braces in position;

50 Fig. 6 is a perspective view of a breakwater;

Fig. 7 is an enlarged detail plan view of a revetment to show the reinforcing; and

Fig. 8 is an enlarged detail end view 55 showing the joint at the top of a pile,

brace and stiffening member and the reinforcing.

Referring now more particularly to the drawing, it will appear that the numeral 10 indicates a reinforced concrete sheet pile formed with a slot 11 along one edge thereof and a rib 12 along the opposite edge. A longitudinally extending opening 13 is further provided in the pile, affording means by which the pile may be sunk into a lake bottom, this being accomplished by jetting water downwardly through the opening to undermine the lake bottom adjacent the lower end of the pile, whereby the pile is sunk to any desired depth.

In a revetment constructed in accordance with the invention, a plurality of piles 10 are sunk in the manner indicated, and are connected together by the rib and slot arrangement. Concrete braces or supports 14 have their lower end portions jetted into the lake bed and the upper end portions of the same are angular in shape and are secured to the upper portions of the piles 10, as shown in Fig. 8. Locking means are provided for said piles and braces 14 and comprise plates 15 cast into the members 14 and extending outwardly. The outer ends of the locking plates 15 are rounded, as at 16, to be received by grooved or semi-circular female locking members 17 formed in the inner faces of the piles 10. Rear braces or supports, comprising vertical portions 18 and diagonal portions 18' are also jetted into place. The revetment top comprises an upstanding front rail 21, a rear rail 19 and transverse members 20 connecting the same, the entire top being integral and cast on the revetment. All of the members of the revetment are reinforced by interpenetrating means 28, as shown in Figs. 7 and 8. If desired, a wooden wale 22 may be bolted to the rail 21, as shown in Fig. 4. The completed revetment is of very strong and permanent construction and is comparatively easy to erect.

Fig. 6 illustrates a breakwater, and the construction of the same is substantially similar to the construction of the revetment, as described. The breakwater is formed of spaced apart walls composed of piles 10. At suitable intervals, the walls are braced and connected by transverse precast concrete stiffening members 24 locked to the piles by locking members 15 and 17, similar to the

locking members described in connection with the revetment, and shown in Fig. 5. The top of the breakwater is finished by a member 25 cast thereon. Crushed stones, 5 concrete or the like is poured between the two walls of the breakwater.

From the foregoing description it will be seen that the improved revetment and breakwater are of very simple and novel construction, and are well adapted for the purposes described.

What I claim as my invention is:

1. A water overflow barrier, comprising a wall formed of a plurality of precast piles 15 having tongue and groove connections, some of said piles having a female locking member of semi-circular shape embedded in the upper portion of the inner face, a top member cast on said wall and engaging said piles, 20 the wall and top member having interpenetrating reinforcing means, brace members engaging said female locking members and said top member and bracing the wall.
2. In a revetment, a wall formed of a plurality of adjacent, partially embedded vertically extending concrete piles having

tongue and groove connections, angularly extending braces for the wall and locked to the upper portions of some of the piles, secondary brace members spaced from the wall 30 and partially embedded, and a horizontal top member cast on said wall and brace members.

3. In a water barrier, a wall formed of a plurality of adjacent, partially embedded, 35 vertically extending concrete piles having tongue and groove connections, angularly extending braces for the wall locked to and engaging only the upper portions of some of the piles, secondary brace members spaced 40 from the wall and partially embedded, and a horizontal top member cast on said wall and brace members and engaging the piles, the angular braces and the secondary brace members, said top member having a rail portion covering the upper portions of the piles, a rear rail portion joining the secondary brace members, and transverse portions connected to the front and rear rails.

In testimony whereof, I affix my signature.

WILLIAM H. GILLEN.
